United States Patent Office

Des. 208,680
Patented Sept. 19, 1967

208,680

WRITING INSTRUMENT

Frank P. Summers, Medford, N.J., assignor to The Esterbrook Pen Company, Cherry Hill, N.J., a corporation of New Jersey

Filed Nov. 2, 1965, Ser. No. 37,982

Term of patent 14 years

(Cl. D74—17)

FIG.1

FIG.2

FIG.3.

FIG.4.

FIG. 1 is a side elevational view of a writing instrument showing my new design;

FIG. 2 is a front elevational view thereof, the back thereto being a mirror image thereof;

FIG. 3 is a side elevational view thereof in writing position with the cap positioned on the back end of the barrel; and

FIG. 4 is a perspective view thereof turned end over end.

I claim:

The ornamental design for a writing instrument, as shown and described.
